UNITED STATES PATENT OFFICE.

FREDERICK J. FEWINGS, OF DULUTH, MINNESOTA.

CAR OR ENGINE REPLACER.

SPECIFICATION forming part of Letters Patent No. 792,977, dated June 20, 1905.

Application filed March 18, 1905. Serial No. 250,849.

To all whom it may concern:

Be it known that I, FREDERICK J. FEWINGS, a citizen of the United States, residing at Duluth, in the county of St. Louis and State of Minnesota, have invented new and useful Improvements in Car or Engine Réplacers, of which the following is a specification.

This invention relates to car and engine replacers; and the object thereof is to provide a car and engine replacer, hereinafter more specifically referred to, which will readily and efficiently replace a car or engine whether it is run forward upon or backed upon the replacer.

Primarily the invention resides in certain improvements hereinafter more specifically set forth upon the forms of car and engine replacers described and claimed in Letters Patent granted to me April 12, 1902, No. 706,542, and April 19, 1904, No. 757,604; and to this end the invention aims to provide a car or engine replacer which shall be simple in construction, strong, durable, efficient in its use, and comparatively inexpensive to manufacture.

With the foregoing and other objects in view the invention consists of the novel construction, combination, and arrangement of parts hereinafter more specifically described, and illustrated in the accompanying drawings, which form a part of this specification, and wherein is shown the preferred embodiment of the invention; but it is to be understood that changes, variations, and modifications can be resorted to which come within the scope of the claims hereunto appended.

In the drawings forming a part of this specification, wherein like reference characters denote corresponding parts throughout the several views, Figure 1 is a perspective view showing the operative position of the replacer-blocks with respect to track-rails. Fig. 2 is a top plan view of the inner replacer-block. Fig. 3 is a top plan view of the outer replacer-block. Fig. 4 is an inverted plan view of the inner replacer-block. Fig. 5 is a like plan view of the outer replacer-block. Fig. 6 is a view looking from one end of the inner replacer-block. Fig. 7 is a section on the line 7 7 of Fig. 2. Fig. 8 is a section on line 8 8,

Fig. 2. Fig. 9 is a section on line 9 9, Fig. 2. Fig. 10 is a section on line 10 10, Fig. 3. Fig. 11 is a section on line 11 11; Fig. 3. Fig. 12 is a section on line 12 12, Fig. 3. Fig. 13 is a section on line 13 13, Fig. 3. Fig. 14 is a section on line 14 14, Fig. 3. Fig. 15 is a perspective view of one of the inner corners of either of the blocks, showing the cut-away portion to permit of straddling the base of the track-rail section. Figs. 16, 17, and 18 show in plan modified forms of blocks.

Referring to the drawings, the inner block will be referred to generally by the reference character 1, and the outer block by the reference character 2. Both of the blocks are hollow, and each is formed of two side walls and a top wall. Each of the blocks is strengthened through the medium of a plurality of transversely-disposed braces 3, arranged within the blocks, intermediate of the ends thereof, and formed integral with the inner face of the side walls and the top wall. In Fig. 1 of the drawings the inner block 1 is shown in operative position with respect to the track-rail section 4, and the outer block 2 is shown in operative position with respect to the track-rail section 5.

The inner block 1 has a curved upper surface with the intermediate part thereof inclined downwardly toward the inner side of the block, and the end portions of said curved upper surface are approximately at right angles with respect to the intermediate part of said surface, said curved surface at its inner part extending in an arc of a circle and at its outer part extending in an arc of a circle of less radius than the arc at the inner part. The manner in which the inner block 1 is constructed, so that the foregoing curvature of the upper surface of the inner block can be obtained, is as follows: That side wall of the inner block 1 which is arranged nearest the rail-section 4 and indicated by the reference character 6 is termed the "inner" wall, and that part of the upper surface of the inner block 1 which is nearest the track-rail section 4 is termed the "inner" part of the curved surface of the block. The side wall 6 is substantially segment-shaped in contour, so that the top edge 7 of said side wall 6 will extend

in an arc of a circle. That side wall of the inner block 1 which is farthest away from the rail-section 4 is termed the "other" side wall 8, and that part of the curved surface of the block which is farthest away from the track-rail section 4 is termed the "outer" part of the curved surface. The side wall 8 extends toward the side wall 6 at an inclination and is what may be termed "bow-shaped" from end to end and is of much greater height than the side wall 6, so as to form a bow-shaped flange 9, arranged with respect to the outer part of the curved surface of the inner block 1, said flange 9 projecting above the curved surface of the block and said curved surface terminating in said flange 9. The top wall of the inner block 1 is indicated by the reference character 10 and is of convexed curvature longitudinally throughout, so that the upper face of said top wall 10 will be curvilinear in contour. The end portions of the top wall 10 at their outer sides curve away from the inner sides, or, in other words, the outer side of the top wall 25 conforms in contour to the side wall 8. The top wall 10 is so constructed that the intermediate portion thereof is inclined downwardly toward the side wall 6, while the end portions of said top wall are inclined at approximately a right angle to the intermediate portion. By such construction the curved upper surface of the block will have an intermediate part which is inclined downwardly toward the side wall 6 and end parts inclined 35 approximately at right angles with respect to said intermediate part. Where the upper surface of the top wall 10 terminates in the flange 9, it extends in the arc of a circle, but of less radius than the top edge 7 of the side wall 6, the said top edge 7 being what may be termed the "terminus" of the inner part of the curved surface of the top wall 10. The lower face of the ends of the top wall is 40 cut away, as at 11, to permit of mounting the block 1 upon the base of the rail-section 4, and said inner face of the top wall is further provided with spurs 12 of any suitable shape and which are adapted to pierce the ties to assist in holding the block 1 rigidly in position. The side wall 8 at its bottom is 45 provided with an outwardly-extending flange 13, which has formed therein a series of openings 14, registering with a series of recesses 15, formed by the depressed portions 16 in the outer face of said wall 8. The recesses and openings are adapted to receive spikes or other suitable fastening means which engage in the ties of the tracks for securing the block 1 thereto when the latter is arranged 50 in its operative position. The bottom of the wall 8 is provided with spurs 17, which are adapted when the block 1 is in position to pierce the ties, so as to assist in retaining said block 1 in its operative position.

65 The outer block 2 is provided with what

may be termed a "hump" of convex curvature longitudinally as well as transversely, the hump inclining downwardly from the outer to the inner side of the block 2 and which is formed by constructing a portion of the block 70 of reversed compound curvature longitudinally and the remaining portion of the block of convexed curvature longitudinally. That portion of the block of convexed curvature longitudinally otherwise than that part into 75 which the hump merges is separated from that portion of the block of reversed compound curvature by a pair of diagonally-extending ribs, which terminate in each side of the hump. The specific manner in which the 80 outer block 2 is constructed so as to obtain the curvature referred to is as follows: That side wall of the outer block 2 which is arranged nearest the track-rail section 5 is indicated by the reference character 18 and is 85 termed the "inner" wall, which is slightly inclined, so as to project away from the rail-section 5, and is substantially segment-shaped in contour, so that the top edge 19 of said side wall 18 will extend in the arc of a circle. The 90 side wall of the outer block 2 which is farthest away from the rail-section 5 is termed the "outer" side wall 20 and extends toward the side wall 18 at an inclination, is of much greater height than the side wall 18, and has 95 its top edge of reversed compound curvature, as at 21. The top wall of the outer block 2 is indicated by the reference character 22 and has a portion thereof of convexed curvature 100 longitudinally and said portion at a point removed from each side of the center spreading outwardly, so that the ends will be enlarged. The other portion of the top wall is of reversed compound curvature, so as to form the hump 23 of convexed curvature longitudinally 105 as well as transversely, and said hump 23 is inclined downwardly toward the inner wall 18 and merges into the intermediate part of that portion of the top wall of convexed curvature longitudinally. The top wall 22 is further provided with a pair of diagonally-extending ribs 24, merging at their upper ends into the hump and further separating the ends of that portion of the top wall of reversed compound curvature from the spreading ends 110 of that portion of the front wall of convexed curvature longitudinally. The upper end of the ribs 24 are not blunt, but are cut away, as at 25, forming at the point where they merge into the hump flattened portions. The 115 lower face at the ends of the top wall is cut away, as at 26, to permit of the mounting of the block 2 upon the base of the track-rail section 5, and said lower face of the ends of the top wall is further provided with spurs 125 27, which are adapted to pierce the ties to assist in retaining the block in position. The side wall 20 at its bottom is provided with an outwardly-extending flange 28, having openings 29, registering with recesses 30, forming 130

passages for holdfast devices for securing the block 2 in position. The lower face of the flange 28 is formed with spurs 31, which are adapted to pierce the ties to assist in retaining the block in position.

By constructing the blocks in the manner as set forth the wheels are prevented from passing completely over them, as the rib on the inner block and the ribs on the outer block 10 guide the wheels and aid the sluing power of the incline, so there is but one place the wheels can go—namely, on the rails. The blocks are so constructed as to be capable of 15 withstanding the weight of the heavy locomotives and are yet light enough to be handled easily. The blocks are high enough to accomplish their work, but do not interfere in any manner with the underrigging of the cars or locomotives. The ascent of each of 20 the blocks is gradual, yet the throwing power is sure, and, furthermore, the blocks can be used on bridges, trestles, curves, boardered 25 crossings, and frozen ground. The providing of the hump on the outer block in a manner as shown causes the wheels to be rerailed even if they should mount the block on the outer side of the ribs, for the reason that the curvature of the hump is such that when the wheels mount it they will be caused to slide toward 30 the inner side of the block so as to be rerailed.

The outer as well as the inner block is provided near each end with a handhold, as at 32 33. These handholds depend from the inner face of the top of their respective blocks and 35 are preferably cylindrical in cross-section and of such size that they can be readily grasped by the trainmen. The handholds 32 33 are in the form of handles and are preferably interposed between the ends of the blocks and 40 the braces 3. The handholds 32 33 preferably extend in a vertical manner and in parallelism with the braces 3.

In the modified construction shown in Fig. 16 the block is indicated by the reference character 34, and in lieu of the ribs 24 the grooves 45 35 are provided, which terminate in the hump 36. Otherwise than that as stated the construction of block shown in Fig. 16 is the same as that shown in Fig. 3.

In Fig. 17 the block is indicated by the reference character 36 and is the same as that shown in Fig. 16, with the exception that a single groove is employed and which is indicated by the reference character 38. On the 55 opposite side of the block a rib 39 is employed in lieu of the groove.

In Fig. 18 a block similar to the construction shown in Fig. 17 is set up, but with this exception, that the rib and groove are reversed. The rib is indicated by the reference character 40, the groove by the reference character 41, and the block by the reference character 42.

Having thus fully described my invention,

what I claim as new, and desire to secure by 65 Letters Patent, is—

1. In a car and engine replacer, an inner block having its upper surface of convexed curvature longitudinally with the intermediate part thereof inclined downwardly toward 70 the inner side of the block and with the end portions of said curved surface inclined approximately at right angles with respect to the intermediate part of said surface.

2. In a car and engine replacer, an inner block having its upper surface of convexed curvature longitudinally with the intermediate part thereof inclined downwardly toward the inner side of the block and with the end portions of said curved surface inclined approximately at right angles with respect to the intermediate part of said surface, said curved 80 surface at its inner part extending in an arc of a circle and at its outer part extending in an arc of a circle of less radius than the arc at 85 the inner part.

3. A car and engine replacer comprising an outer replacer-block having a curved upper surface with the inner part thereof of convexed curvature longitudinally and the outer 90 part thereof of reversed compound curvature longitudinally, thereby forming a hump of convexed curvature longitudinally as well as transversely, said hump terminating in the intermediate part of said part of convexed 95 curvature longitudinally.

4. A car and engine replacer comprising an outer replacer-block having a curved upper surface with the inner part thereof of convexed curvature longitudinally and the outer 100 part thereof of reversed compound curvature longitudinally, thereby forming a hump of convexed curvature longitudinally as well as transversely, said hump terminating in the intermediate part of said part of convexed 105 curvature longitudinally, and ribs for separating portions of the part of convexed curvature longitudinally from portions of the part of reversed compound curvature longitudinally, said ribs at their upper ends merging 110 into said hump.

5. A car and engine replacer comprising an outer replacer-block having a curved upper surface with the inner part thereof of convexed curvature longitudinally and the outer 115 part thereof of reversed compound curvature longitudinally, thereby forming a hump of convexed curvature longitudinally as well as transversely, said hump terminating in the intermediate part of said part of convexed 120 curvature longitudinally, and diagonally-extending ribs for separating portions of the part of convexed curvature longitudinally from portions of the part of reversed compound curvature longitudinally, said ribs at 125 their upper ends merging into said hump.

6. A car and engine replacer comprising an outer replacer-block having a curved upper

surface with the inner part thereof of convexed curvature longitudinally and the outer part thereof of reversed compound curvature longitudinally, thereby forming a hump of 5 convexed curvature longitudinally as well as transversely, said hump terminating in the intermediate part of said part of convexed curvature longitudinally, and diagonally-extending ribs for separating portions of the 10 part of convexed curvature longitudinally from portions of the parts of reversed compound curvature longitudinally, said ribs at their upper ends merging into said hump, said block having the intermediate part of its outer 15 wall of greater height than the intermediate part of its inner wall.

7. In a car and engine replacer, an inner block having its upper surface of convexed curvature longitudinally with the intermediate 20 part thereof inclined downwardly toward the inner side of the block and with the end portions of said curved surface inclined approximately at right angles with respect to the intermediate part of said surface, said 25 block having the intermediate part of its outer wall of greater height than the intermediate part of its inner wall.

8. In a car and engine replacer, an inner block having its upper surface of convexed 30 curvature longitudinally with the intermediate part thereof inclined downwardly toward the inner side of the block and with the end portions of said curved surface inclined approximately at right angles with respect to 35 the intermediate part of said surface, said curved surface merging at its outer part into an upwardly-extending flange.

9. A car and engine replacer comprising a hollow inner replacer-block consisting of an 40 inner side wall and an outer side wall, said inner wall substantially segment-shaped in contour, said outer side wall extending toward the inner wall at an inclination and substantially bow-shaped in contour and of much 45 greater height than the inner wall, a top wall of convexed curvature longitudinally formed integral with the said side walls and terminating at its outer side in an upwardly-extending flange conforming in contour to the outer 50 side wall, the end portions of said top wall curving outwardly and inclined approximately at right angles with respect to the intermediate portion of said top wall, and said top wall having its lower face cut away so as to permit of 55 mounting a rail-section and further provided with integral piercing-spurs, and said side wall at its bottom terminating in an outwardly-extending flange provided with a series of openings registering with a series of recesses.

60 10. A car and engine replacer comprising a hollow inner replacer-block consisting of an inner side wall and an outer side wall, said inner wall substantially segment-shaped in contour, said outer side wall extending toward 65 the inner wall at an inclination and substan-

tially bow-shaped in contour and of much greater height than the inner wall, a top wall of convexed curvature longitudinally formed integral with the said side walls and terminating at its outer side in an upwardly-extending flange conforming in contour to the outer side wall, the end portions of said top wall curving outwardly and inclined approximately at right angles with respect to the intermediate portion of said top wall, and said top wall having its lower face cut away so as to permit of mounting a rail-section and further provided with integral piercing-spurs, and said side wall at its bottom terminating in the outwardly-extending flange provided with a series of openings registering with a series of recesses, and a plurality of transversely-disposed braces arranged within said block intermediate the ends thereof and formed integral with the inner face of the side 80 walls and the lower face of the top walls.

11. A car and engine replacer comprising a hollow outer replacing-block consisting of an inner wall slightly inclined so as to project away from a track-rail section and substantially segment-shaped in contour, an outer wall extending toward the inner wall at an inclination and having its top edge of reversed compound curvature, and a top wall formed integral with the side walls and having a portion thereof of convexed curvature longitudinally with the ends thereof spreading outwardly, said top wall having its other portion of reversed compound curvature longitudinally so as to form a hump of convexed curvature longitudinally as well as transversely, said hump inclining downwardly toward the inner wall and merging into the intermediate part of that portion of the top wall of convexed curvature longitudinally, and a pair of diagonally-extending ribs merging at their upper ends into said hump and separating the ends of that portion of the top wall of reversed compound curvature from the spreading ends of that portion of the front wall of convexed curvature, said top wall having its lower face at the ends thereof cut away to permit of mounting the block upon the base of a track-rail section and further provided with integral piercing-spurs, and said outer side wall terminating at its bottom with an outwardly-extending flange provided with openings registering with recesses and further provided with integral piercing-spurs.

12. A car and engine replacer comprising a hollow outer replacing-block consisting of an inner wall slightly inclined so as to project away from a track-rail section and substantially segment-shaped in contour, an outer wall extending toward the inner wall at an inclination and having its top edge of reversed compound curvature, and a top wall formed integral with the side walls and having a portion thereof of convexed curvature longitudinally with the ends thereof spreading out-

wardly, said top wall having its other portion of reversed compound curvature longitudinally so as to form a hump of convexed curvature longitudinally as well as transversely, 5 said hump inclining downwardly toward the inner wall and merging into the intermediate part of that portion of the top wall of convexed curvature longitudinally, and a pair of diagonally-extending ribs merging at their upper 10 ends into said hump and separating the ends of that portion of the top wall of reversed compound curvature from the spreading ends of that portion of the front wall of convexed curvature, said top wall having its lower face 15 at the ends thereof cut away to permit of mounting the block upon the base of a track-rail section and further provided with integral piercing-spurs, and said outer side wall terminating at its bottom with an outwardly-extending 20 flange provided with openings registering with recesses and further provided with integral piercing-spurs, and a plurality of transversely-disposed braces arranged within said block intermediate the ends thereof and 25 formed integral with the inner face of the side walls and the lower face of the top wall.

13. A car and engine replacer comprising an inner and an outer replacer-block, said inner block of convexed curvature longitudinally 30 with the intermediate portion thereof inclined approximately at right angles with respect to the end portions thereof, and said outer block having a portion thereof of convexed curvature longitudinally and the other portion of 35 reversed compound curvature longitudinally forming thereby a hump inclining toward and terminating in that portion of convexed curvature longitudinally.

14. A car and engine replacer comprising an 40 inner and an outer replacer-block, said inner block of convexed curvature longitudinally with the intermediate portion thereof inclined approximately at right angles with respect to the end portions thereof, and said outer block 45 having a portion thereof of convexed curvature longitudinally and the other portion of reverse compound curvature longitudinally forming thereby a hump inclining toward and terminating in that portion of convexed curvature 50 longitudinally, and said outer block further provided with a pair of diagonally-extending ribs terminating in the hump and separating parts of the portion of convexed curvature longitudinally from parts of the portion 55 of reversed compound curvature longitudinally.

15. A car and engine replacer comprising an inner and an outer replacer-block, said inner block of convexed curvature longitudinally 60 with the intermediate portion thereof inclined approximately at right angles with respect to the end portions thereof, and said outer block having a portion thereof of convexed curvature longitudinally and the other portion of 65 reversed compound curvature longitudinally

forming thereby a hump inclining toward and terminating in that portion of convexed curvature longitudinally, and said outer block further provided with a pair of diagonally-extending ribs terminating in the hump and separating parts of the portion of convexed curvature longitudinally from parts of the portion of reversed compound curvature longitudinally, and said outer block at its outer side provided with an upwardly-extending bow-shaped 70 flange. 75

16. A replacer-block having a curved upper surface with the terminus at one side thereof extending in the arc of a circle and the terminus at the other side thereof extending 80 throughout in the arc of a circle, the arc of one side being of less radius than the arc at the other side, the terminus of said curved upper surface at one side thereof, merging in an inwardly and longitudinally extending 85 flange.

17. A replacer-block having a curved upper surface with the outer side terminus thereof extending throughout in the arc of a circle and the inner side terminus thereof extending 90 in the arc of a circle, the arc of the outer side of less radius than the arc of the inner side, said outer side terminus of the curved upper surface merging into a vertically and longitudinally extending flange of a length substantially equal to that of the block. 95

18. A replacer-block having the top thereof formed in a curvilinear manner with the intermediate part thereof inclined downwardly toward the inner side of the block and with 100 the end portions of said top inclined approximately at right angles with respect to the intermediate part thereof, and handholds depending from the lower face of said top.

19. A replacer-block having a curved upper 105 surface with the terminus at one side thereof extending in the arc of a circle and the terminus at the other side thereof extending in the arc of a circle, the arc of one side being of less radius than the arc at the other side, 110 and depending handholds arranged within said block.

20. A replacer-block having a curved upper surface with the outer side terminus thereof extending in the arc of a circle and the inner 115 side terminus thereof extending in the arc of a circle, the arc of the outer side of less radius than the arc of the inner side, and depending handholds arranged within said block.

21. In a car and engine replacer, an inner 120 block having a curved upper surface with the intermediate part thereof inclined downwardly toward the inner side of the block and with the end portions of said curved surface inclined approximately at right angles with 125 respect to the intermediate part of said surface, and depending handholds arranged within the block and formed integral therewith.

22. In a car and engine replacer, an inner 130 block having a curved upper surface with the

intermediate part thereof inclined downwardly toward the inner side of the block and with the end portions of said curved surface inclined approximately at right angles with respect to the intermediate part of said surface, said curved surface at its inner part extending in an arc of a circle and at its outer part extending in an arc of a circle of less radius than the arc at the inner part, and depending handholds arranged within the block and formed integral therewith.

23. A car and engine replacer comprising an outer replacer-block having a curved upper surface with the inner part thereof of convexed curvature longitudinally and the outer part thereof of reversed compound curvature longitudinally, thereby forming a hump of convexed curvature longitudinally as well as transversely, said hump terminating in the intermediate part of said part of convexed curvature longitudinally, and depending handholds arranged within the block and formed integral therewith.

24. A car and engine replacer comprising an outer replacer-block having a curved upper surface with the inner part thereof of convexed curvature longitudinally and the outer part thereof of reversed compound curvature longitudinally, thereby forming a hump of convexed curvature longitudinally as well as transversely, said hump terminating in the intermediate part of said part of convexed curvature longitudinally, ribs for separating portions of the part of convexed curvature longitudinally from portions of the part of reversed compound curvature longitudinally, said ribs at their upper ends merging into said hump, and depending handholds arranged within the block and formed integral therewith.

25. A car and engine replacer comprising an outer replacer-block having a curved upper surface with the inner part thereof of convexed curvature longitudinally and the outer part thereof of reversed compound curvature longitudinally, thereby forming a hump of convexed curvature longitudinally as well as transversely, said hump terminating in the intermediate part of said part of convexed curvature longitudinally, diagonally-extending ribs for separating portions of the part of convexed curvature longitudinally from portions of the part of reversed compound curvature longitudinally, said ribs at their upper ends merging into said hump, and depending handholds arranged within the block and formed integral therewith.

26. A car and engine replacer comprising an outer replacer-block having a curved upper surface with the inner part thereof of convexed curvature longitudinally and the outer part thereof of reversed compound curvature longitudinally, thereby forming a hump of convexed curvature longitudinally as well as

transversely, said hump terminating in the intermediate part of said part of convexed curvature longitudinally, diagonally-extending ribs for separating portions of the part of convexed curvature longitudinally from portions of the parts of reversed compound curvature longitudinally, said ribs at their upper ends merging into said hump, said block having the intermediate part of its outer wall of greater height than the intermediate part of its inner wall, and depending handholds arranged within the block and formed integral therewith.

27. In a car and engine replacer, an inner block having a curved upper surface with the intermediate part thereof inclined downwardly toward the inner side of the block and with the end portions of said curved surface inclined approximately at right angles with respect to the intermediate part of said surface, said block having the intermediate part of its outer wall of greater height than the intermediate part of its inner wall, and depending handholds arranged within the block and formed integral therewith.

28. In a car and engine replacer, an inner block having a curved upper surface with the intermediate part thereof inclined downwardly toward the inner side of the block and with the end portions of said curved surface inclined approximately at right angles with respect to the intermediate part of said surface, said curved surface merging at its outer part into an upwardly-extending flange, and depending handholds arranged within the block and formed integral therewith.

29. A car and engine replacer comprising a hollow inner replacer-block consisting of an inner side wall and an outer side wall, said inner wall substantially segment-shaped in contour, said outer side wall extending toward the inner wall at an inclination and substantially bow-shaped in contour and of much greater height than the inner wall, a top wall of convexed curvature longitudinally formed integral with the said side walls and terminating at its outer side in an upwardly-extending flange conforming in contour to the outer side wall, the end portions of said top wall curving outwardly and inclined approximately at right angles with respect to the intermediate portion of said top wall, and said top wall having its lower face cut away so as to permit of mounting a rail-section and further provided with integral piercing-spurs, and said side wall at its bottom terminating in an outwardly-extending flange provided with a series of openings registering with a series of recesses, and handholds arranged within the block, depending from and formed integral with the lower face of said top wall.

30. A car and engine replacer comprising a hollow inner replacer-block consisting of an inner side wall and an outer side wall, said in-

ner wall substantially segment-shaped in contour, said outer side wall extending toward the inner wall at an inclination and substantially bow-shaped in contour and of much greater height than the inner wall, a top wall of convexed curvature longitudinally formed integral with the said side walls and terminating at its outer side in an upwardly-extending flange conforming in contour to the outer side wall, the end portions of said top wall curving outwardly and inclined approximately at right angles with respect to the intermediate portion of said top wall, and said top wall having its lower face cut away so as to permit of mounting a rail-section and further provided with integral piercing-spurs, and said side wall at its bottom terminating in the outwardly-extending flange provided with a series of recesses, a plurality of transversely-disposed braces arranged within said block intermediate the ends thereof and formed integral with the inner face of the side walls and the lower face of the top walls, and handholds formed integral with and depending from the top wall of the block and interposed between the said braces and the ends of the blocks.

31. A car and engine replacer comprising a hollow outer replacing-block consisting of an inner wall slightly inclined so as to project away from a track-rail section and substantially segment-shaped in contour, an outer wall extending toward the inner wall at an inclination and having its top edge of reversed compound curvature, and a top wall formed integral with the side walls and having a portion thereof of convexed curvature longitudinally with the ends thereof spreading outwardly, said top wall having its other portion of reversed compound curvature longitudinally so as to form a hump of convexed curvature longitudinally as well as transversely, said hump inclining downwardly toward the inner wall and merging into the intermediate part of that portion of the top wall of convexed curvature longitudinally, a pair of diagonally-extending ribs merging at their upper ends into said hump and separating the ends of that portion of the top wall of reversed compound curvature from the spreading ends of that portion of the front wall of convexed curvature, said top wall having its lower face at the ends thereof cut away to permit of mounting the block upon the base of a track-rail section and further provided with integral piercing-spurs, and said outer side wall terminating at its bottom with an outwardly-extending flange provided with openings registering with recesses and further provided with integral piercing-spurs, a plurality of transversely-disposed braces arranged within said block intermediate the ends thereof and formed integral with the inner face of the side walls and the lower face of the top wall, and handholds formed integral with and depending from the lower face of said top wall and interposed between the braces and the ends of the blocks.

33. A hollow replacer-block having interiorly-arranged depending handholds.

34. A hollow replacer-block having a curved upper surface and depending handholds.

35. A hollow replacer-block having depending handholds.

36. A replacer-block having a curved upper surface and depending handholds.

37. A replacer-block having a handhold near each end thereof.

In testimony whereof I have hereunto set my hand in presence of two subscribing witnesses.

FREDERICK J. FEWINGS.

Witnesses:

C. J. GRIFFIN,
F. R. MCKENZIE.

integral with and depending from the lower face of the top wall.

32. A car and engine replacer comprising a hollow outer replacing-block consisting of an inner wall slightly inclined so as to project away from a track-rail section and substantially segment-shaped in contour, an outer wall extending toward the inner wall at an inclination and having its top edge of reversed compound curvature, and a top wall formed integral with the side walls and having a portion thereof of convexed curvature longitudinally with the ends thereof spreading outwardly, said top wall having its other portion of reversed compound curvature longitudinally so as to form a hump of convexed curvature longitudinally as well as transversely, said hump inclining downwardly toward the inner wall and merging into the intermediate part of that portion of the top wall of convexed curvature longitudinally, a pair of diagonally-extending ribs merging at their upper ends into said hump and separating the ends of that portion of the top wall of reversed compound curvature from the spreading ends of that portion of the front wall of convexed curvature, said top wall having its lower face at the ends thereof cut away to permit of mounting the block upon the base of a track-rail section and further provided with integral piercing-spurs, and said outer side wall terminating at its bottom with an outwardly-extending flange provided with openings registering with recesses and further provided with integral piercing-spurs, a plurality of transversely-disposed braces arranged within said block intermediate the ends thereof and formed integral with the inner face of the side walls and the lower face of the top wall, and handholds formed integral with and depending from the lower face of said top wall and interposed between the braces and the ends of the blocks.

33. A hollow replacer-block having interiorly-arranged depending handholds.

34. A hollow replacer-block having a curved upper surface and depending handholds.

35. A hollow replacer-block having depending handholds.

36. A replacer-block having a curved upper surface and depending handholds.

37. A replacer-block having a handhold near each end thereof.

In testimony whereof I have hereunto set my hand in presence of two subscribing witnesses.
